UNITED STATES PATENT OFFICE.

PAUL DUPONT, OF PARIS, FRANCE, ASSIGNOR TO CHENEY BROTHERS, OF SOUTH MANCHESTER, CONNECTICUT, A CORPORATION OF CONNECTICUT.

DESIGN FOR TEXTILE FABRIC.

• 41,906.

Specification for Design.

Patented Nov. 7, 1911.

Application filed August 3, 1911. Serial No. 642,122½. Term of patent 3½ years.

To all whom it may concern:

Be it known that I, PAUL DUPONT, a citizen of France, residing at Paris, France, have invented a new, original, and ornamental Design for Textile Fabrics, of which the following is a specification, reference being had to the accompanying drawings, forming a part thereof.

The single figure of the drawing is a plan

view of a portion of a textile fabric illustrating my new design.

I claim:

The ornamental design for a textile fabric, as shown.

P. DUPONT.

Witnesses:

H. C. COXE,
JACK G. A. BAKER.
